UNITED STATES PATENT OFFICE.

HARRY A. SUTTON, OF DAYTON, OHIO.

SYNCHRONIZING GUN CONTROL.

Application filed May 11, 1923. Serial No. 638,283.

To all whom it may concern:

Be it known that I, HARRY A. SUTTON, a citizen of the United States, residing at Dayton, in the county of Montgomery and 5 State of Ohio, have invented certain new and useful Improvements in Synchronizing Gun Controls, of which the following is a specification.

This invention relates to synchronizing 10 gun controls and is an improvement upon the control at present in use in which the trigger of a machine gun is synchronously operated with the speed of the engine.

The object of this invention is to provide 15 an improved impulse generating unit in which an impulse lever is operated by the impulse cam and in which a bell crank lever is adapted to be moved into and out of position between the cam and the impulse 20 lever so as to serve as an idler while transmitting impulses to the impulse lever.

Other objects will be more fully set forth in the attached specification and claims. In 25 the drawings:

Fig. 1 is a vertical section of the impulse 30 generator and operating lever and showing the impulse generator geared to the airplane engine shaft.

Fig. 2 is a transverse section on the line 35 2—2 of Fig. 1.

Fig. 3 is a section of the hand operated control cable as mounted on the airplane control lever.

Fig. 4 is a vertical section through part 40 of the impulse generator.

Fig. 5 is a section on the line 5—5 of Fig. 4.

Fig. 6 represents a trigger motor which 45 is mounted on the machine gun.

Referring to the drawings by reference numerals, the bevel gear 1 which is driven 50 from the engine shaft of an airplane, is geared to a vertical shaft 2 by means of bevel gear 3. This shaft 2 is held by suitable bearings in a supporting housing 4 and is provided at its upper end with a cam 5. This cam which is fixed to and rotates with the shaft 2, is provided with two projections 6—6 which are adapted to generate 55 impulses which are transmitted in a manner which will now be described.

A bell crank lever 6 is pivoted by means of a pin 7 on the main supporting housing 4 and the vertically and downwardly ex-

tending leg of this bell crank lever or rocker 55 arm is positioned close to the cam 6. The horizontally extending leg of the rocker arm 6 is connected to a vertically extending flexible wire 8 which extends through a tubing 9 to the trigger motor 10 which is mounted on the machine gun, the flexible wire 8 being connected to a lever 11 pivoted at 12 on the trigger motor so that when the rocker arm 6 pulls downwardly on the wire 8, 13 the lever 11 will be moved to the left against 18 the tension of a spring (not shown) within 15 the trigger motor. The motion of this lever 11 operates the trigger to fire the gun.

A second bell crank lever 13 consists of 20 a horizontally extending rod 14 and a downwardly extending curved portion 15. This bell crank lever is adapted to rotate about the axis of the horizontal portion 14 by means of suitable ball bearings 16 and the bell crank lever is also permitted to pivot 25 about a horizontal axis so that the horizontal portion 14 can move downwardly from the position shown in Fig. 5 to a limited degree. This pivotal motion of the bell crank is provided for by means of a special ball bearing having a curved race, in order to allow this pivotal movement as 30 well as a rotational one.

The downwardly extending portion 15 of the bell crank lever 13 is provided with an 35 enlargement 17 and with a tapering tail portion 18. When the lever is in the position as shown in the Fig. 5, the enlarged portion 17 is positioned between the cam 5 and rocker arm 6 and serves as an idler in 40 transmitting impulses from the generator cam 5 to the rocker arm 6. When, however, the bell crank lever 13 has been moved counter-clockwise from this position, the enlarged portion 17 is moved out of this 45 position and the tapering tail portion 18 is now moved between the cam and the rocker arm 6; but this tapering tail portion is not sufficiently wide to transmit motions of the cam to the impulse lever 6. The enlarged projection 17 in this position engages 50 with a stop 19 on housing 4 to hold the tail portion 18 away from the cam. It will, therefore, be seen that with the bell crank operating lever in one position, impulses are 55 generated by the cam and transmitted to the impulse lever and to the trigger motor and with the bell crank lever 13 in a dif-

ferent position, no impulses will be transmitted to the impulse lever, and consequently, the gun will not be operated.

In order to operate the bell crank lever, 5 a small pin or projection 20 is provided in the end of this horizontal arm 14 of the bell crank lever and extends into a slot 21 in a vertically reciprocating member or plunger 22. This plunger is adapted to 10 move vertically within a hole 23 in the housing 4. The plunger 22 is connected to a flexible cable or wire 24 and is normally urged downwardly by means of spring 25 acting upon the upper end of this plunger. 15 The cable or wire 24 is connected as shown in Fig. 3 to a hand lever 26 which bears against a projection 29 on a bracket 28 which is suitably mounted upon the airplane control lever as shown in Fig. 3. The 20 control cable 24 is connected to the lever 26 by means of a pin 27 so that as the hand lever 26 is moved to the dotted position, a pull will be exerted upon a cable 24 to raise the plunger and cause the enlarged 25 projection on the bell crank lever 13 to be moved into its impulse transmitting position. When the hand lever is released, the spring 25 returns the bell crank lever and the handle 26 to their normal positions.

30 I claim:

1. In a synchronizing gun control, in combination, a housing, an impulse generator cam mounted in said housing, an impulse lever operated by said cam and adapted to 35 be connected to a trigger operating mechanism, a bell crank lever mounted on said housing, an enlarged projection on said bell crank lever, and a manually operated device connected to said bell crank lever so as 40 to move the said enlarged portion into position between the cam and the impulse lever.

2. In a synchronizing gun control, in combination, a housing, an impulse generator cam mounted in said housing, an impulse lever operated by said cam and adapted to 45 be connected to a trigger operating mechanism, a bell crank lever mounted on said housing, an enlarged projection on said bell crank lever, a manually operated device connected to said bell crank lever so as 50 to move the said enlarged portion into position between the cam and the impulse lever so as a bell crank lever serves as an idler in transmitting impulses from said cam to said 55 impulse lever, and yielding means normally

tending to move said enlarged projection out of said position so that movements of cam will not be transmitted to the impulse lever.

3. In a synchronizing gun control, in combination, a housing, a rotary impulse generator shaft adapted to be driven from the engine, a cam on said shaft, a bell crank impulse lever pivoted on said housing and operated by said cam and connected to a trigger motor for operating the same, a bell crank operating lever pivotally mounted on the housing, an enlarged portion on said operating lever, and a manually operated device connected to said operating lever so as to move the said enlarged portion into or 70 out of position between the cam and the impulse lever.

4. In a synchronizing gun control, in combination, a housing, a rotary impulse generator shaft adapted to be driven from the engine, a cam on said shaft, a bell crank operating lever movably mounted on said housing so as to be movable about a plurality of axes, an enlarged portion on said operating lever, a reciprocating member connected to one end of the said operating lever, a spring means normally urging said member in one direction, a manually operated device connected to said member to operate the member against tension of the spring, 80 said member when operated by the manually operated device adapted to move the enlarged portion of the operating lever into position between the cam and an impulse lever to serve as an idler in transmitting 85 motion between the cam and the impulse lever, and a flexible connection between the impulse lever and trigger operating mechanism.

5. In a synchronizing gun control, in combination, a housing, an impulse generator cam mounted in said housing, an impulse lever operated by said cam and adapted to be connected to a trigger operating mechanism, a second lever mounted on said housing, a stop on the housing, an enlarged projection on said second lever, and a manually operated device connected to said second lever so as to move the said enlarged portion into position between the cam and the impulse lever or to move the enlarged projection against said stop to hold the end of the said second lever away from the cam.

In testimony whereof I affix my signature.

HARRY A. SUTTON.
